SAMPLE CASE

Lloyd W. Plummer, Bloomington, Ill.

Application August 2, 1933, Serial No. 683,398

2 Claims. (Cl. 190—17)

This invention relates to a sample case for use in the display of specimens of merchandise such as groceries, jewelry, candy, etc. and it is designed for use especially upon the structure disclosed in my co-pending application filed July 1, 1933, Serial Number 678,674.

It is an object of the invention to provide a case which is more sturdy in construction than heretofore, there being provided a double link 10 connection between the several trays of the case whereby the series of trays which are provided, will not buckle when extended from their normal or closed positions but will be supported in a more rigid manner than heretofore.

15 A further object is to provide a specially reinforced structure of this character wherein series of trays can be mounted either for vertical or for oblique lift, depending upon the requirements of the user, it being possible to produce said series of trays as units and to assemble them with the base portion of the structure in such a way as to produce either type of case, namely, a vertical lift or an oblique lift.

With the foregoing and other objects in view 25 which will appear as the description proceeds, the invention consists of certain novel features of construction and arrangement of parts herein-after more fully described and pointed out in the claims, it being understood that changes may 30 be made in the construction and arrangement of parts without departing from the spirit of the invention as claimed.

In the accompanying drawings the preferred forms of the invention have been shown.

35 In said drawings:

Figure 1 is a perspective view of one end portion of a case embodying the present improvements, parts being broken away and one of the series of trays being shown in its normal or 40 closed position while the other series is extended obliquely.

Figure 2 is an end elevation of a portion of a modified form of case wherein the trays are mounted for a vertical lift.

45 Figure 3 is an enlarged end elevation of the form shown in Figure 2 showing the tray lifted vertically.

In the present invention two series of trays are provided. These trays, which have been indicated generally at 1, are duplicates and normally rest one upon the other. The trays are connected at both ends by a novel arrangement of links and levers and as the connections at both ends are the same it has been deemed necessary 55 to illustrate only those connections at one end.

As shown in Figure 1 the series of trays are supported on a base 2 and extended half-way across the base from side to side. Thus when the trays of both series are in their normal or closed positions they will extend throughout the 60 width of the base.

Each of the trays 1, except the top tray, has a pair of parallel inclined levers 3 and 3' fulcrumed thereon at 4, the fulcrums being positioned along the horizontal center line of the 65 end of the tray and equidistant from the vertical center thereof. One of the levers 3 has an arm 5 extended upwardly above its tray and pivotally attached at 6 to the tray thereabove at a point in alinement with the fulcrums 4.

70 The lever 3' on each tray has a downwardly extended arm 7 pivotally connected at 8 to the next adjoining tray. Thus each of the trays 1 except the top one is provided at each end with four alining fulcrum points indicated at 8, 4, 4 75 and 6.

The upper end of each lever 3' is connected to the adjacent lever 3 of the same tray by a link 9 and another link 10 connects the lower end of said lever 3 to its companion lever 3'. These two 80 links are parallel and, with levers 3 and 3', form a parallelogram. The lower tray of the series is connected at each end to its base 2 by pivotally joining the arm 7 of its lever 3' to the base as indicated at 11. It is also joined to the base by an 85 elongated link 12 pivotally attached to the base at 13 and to the bottom trays 1 at 14. A similar arrangement is provided for joining the upper tray 1 to the next adjoining tray thereunder. The arm 5 of lever 3 being pivotally attached to 90 the upper tray at 15 while an elongated link 16 which is parallel to lever 3 is pivotally joined at its lower end 17 to the adjacent tray 1 while its upper end is pivotally attached to the upper tray as shown at 18.

95 With the tray connected as described it will be noted that each tray is joined at its end to the next adjoining tray by two levers or a lever and a link, thereby insuring rigid support of each tray when it is lifted obliquely as shown at the right of Figure 1. Thus there is no danger of the tray sagging when extended outwardly for display purposes and a more substantial structure is provided than would be possible otherwise.

100 It will be noted that each series of trays constitutes a complete unit, these units being oppositely disposed so that the trays of the units, in the structure shown in Figure 1, can be lifted obliquely so as to diverge upwardly.

105

110

Should it be desired to produce a case having series of trays arranged for vertical lifts the same assembly would be used in the construction of the units with this modification, namely, the positions of the two series of trays illustrated in Figure 1 would be reversed, the links 12 and the arms 7 would be dispensed with and the inner sides of the trays would be pivotally connected at their lower corners as indicated at 19 in Figures 2 and 10 3. Instead of joining the series of trays to their base 20 by means of links 12 and arms 7, each of the lower trays of the two series will be connected to the base by a lever 21. The levers normally diverge downwardly and are joined by crossed links 22 attached to the levers 21 above and below and at equal distances from their fulcrums 23. Thus by pulling upwardly on the two series of trays as shown in Figure 3 they will tilt about their pivotal connections 24 with the levers 21 15 and will assume inclined positions as shown in Figure 3, the trays of each series being inclined oppositely to the corresponding trays of the other series to which they are pivotally connected at 19.

It will be noted that in the structure shown in Figures 2 and 3 the same arrangement of parallelograms made up of levers 3 and 3' is provided as in Figure 1, these levers being joined by the parallel links 9 and 10.

A latch rod 25 is pivotally connected to one of the trays of one series and is slidable in an eye 26 on the corresponding tray of the other series, this rod being formed with an off-set 27 and being provided with a spring 28 whereby off-set can be shifted into engagement with the eye to hold the trays in their elevated and inclined positions.

Importance is attached to the fact that by connecting the trays in the manner described the units can be assembled in quantities and subsequently can be used either in an oblique lift construction such as shown in Figure 1 or a vertical lift construction as shown in Figures 2 and 3.

When so produced they are provided with projecting ears 29 for receiving the pivots 19 but these ears can be cut off readily if the units are to be assembled as in Figure 1.

What is claimed is:

1. A unit for use in vertical or oblique lift display cases comprising superposed trays normally resting one upon the other, a pair of levers fulcrumed between their ends upon the end of each tray, one lever of each pair having a downwardly extended arm pivotally connected at its lower end to the next adjoining tray thereunder and the other lever of each pair having an upwardly extended arm pivotally connected to the next adjoining tray thereabove, all of the levers being parallel and the pivotal connections between each tray and all of the levers thereon being disposed in alinement, and parallel links connecting the levers of each pair and cooperating therewith to provide a parallelogram.

2. In a device of the class described a base, and opposed display units mounted on the base, each unit comprising a series of superposed trays normally resting one upon the other, movable means connecting the lower tray of each unit to the base and permitting relative movement of the two units, and connections between the trays at each end, said connections including a pair of parallel levers pivotally connected between their ends to the end of each tray, one of the levers having a downwardly extending arm pivotally connected to the next adjoining tray thereunder and the other lever of each pair having an upwardly extending arm pivotally joined to the next adjoining tray thereabove, the pivotal connections between all of the levers and any one of the trays being disposed in alinement, and parallel link connections between the levers of each pair above and below the fulcrums of said levers.
